FIG. 2

UNITED STATES PATENT OFFICE

2,621,776

BARN CLEANER

Wilfred E. Hedlund and Martin R. Hedlund,
Boyceville, Wis.

Application April 10, 1947, Serial No. 740,656

4 Claims. (Cl. 198—108)

1

This invention relates to barn cleaners adapted to clean the conventional floor gutters found in most dairy barns. As is well understood in the art, these gutters lie lengthwise of the barn a short distance outwardly from the open ends of the cattle stalls or the same relative distance with respect to cattle stanchions if the stalls are not provided.

It is an object of the invention to provide a barn cleaning device which includes an elongated flexible material conveyor which moves lengthwise in the gutter to drag material therefrom, and wherein means is provided for conveniently returning the elongated flexible conveyor unit to a position where it can be quickly and easily redeposited in the gutter for a succeeding cleaning operation.

Another object of the invention is to provide apparatus of the type mentioned above in combination with conveniently located power means for moving the conveyor through its gutter cleaning movement and returning it to a position for a succeeding cleaning operation.

Still a further object of the invention is to provide barn cleaning apparatus of the type described above in combination with an outrigger along which the conveyor is moved to deposit the droppings or other material from the gutter at a point outside the barn and to guide the conveyor in its return movement.

The above and other objects and advantages of the invention will more fully appear from the following description made in connection with the accompanying drawings, wherein like reference characters refer to the same parts throughout the views, and, in which:

Figure 1 is a longitudinal vertical sectional view through the lower portion of a dairy barn showing our apparatus in side elevation;

Figure 2 is a fragmentary plan view of the lower portion of a barn with the cleaning apparatus shown in plan with portions of the housing of the power unit broken away;

Figure 3 is an enlarged fragmentary side elevational view of the outrigger's discharge showing its hinged discharge gate in closed and open position in full and dotted lines respectively;

Figure 4 is a fragmentary plan view of the elongated flexible conveyor structure;

Figure 5 is an enlarged transverse sectional view through the conveyor structure; and

Figure 6 is a fragmentary plan view of one of the conveyor cross members showing its connection with one of the side chains.

In Figures 1 and 2 there is illustrated a portion

2

of a dairy barn 7 having a floor 8, end walls 9 and 10, a side wall 11, and a ceiling 12. In the barn floor 8 is a conventional gutter 13 which extends along the open rear ends of a series of cattle stalls 14. The right hand end of the gutter 13 is its discharge end and the side wall 10 is provided with a gutter discharge opening 15. A second opening 16 is provided in the side wall 10 for a purpose to be described below.

An elongated flexible conveyor member 17 is shown made up of a pair of side chains 18 whose ends converge and are connected by rings 19 as clearly shown in Figures 2 and 4. The side chains 18 are connected by cross members 20 which are provided at their ends with loops 21 which are adapted to receive a side of each of a pair of oppositely disposed side chain links 18a, as shown in Figures 2, 4, 5 and 6. As best illustrated in Figure 5, the conveyor cross members 20 are of such thickness that they will rest upon and slide along the bottom of the barn gutter 13.

Extending outwardly and upwardly from the gutter discharge opening in the barn side wall 10 is an outrigger indicated generally at 22. The outrigger includes a bottom 23 and side walls 24. At the outer end thereof the bottom 23 is provided with a hinged gate 25 releasably held by a suitable catch device 26 mounted on one or both of the outrigger side members 24. At the outer ends of the outrigger side members 24 is a cross shaft 27 which carries a roller 28. A second roller 29 is carried between the side members 24 rearwardly of the roller 28. At the inlet or lower end of the outrigger 22 are shoes 30 which extend inwardly a short distance from each side member 24 and are positioned a short distance above the interior of the outrigger bottom 23. The left hand ends of the shoes 30 are shown in Figure 1 extending through the gutter outlet opening 15 in the barn side wall 10. In the opening 16 above the opening 15 is mounted a guide member or roller 31 which is positioned adjacent the top of said opening 16 leaving a substantial space between the underside of the roller and the bottom of said opening.

Connected to the right hand or return end of the flexible conveyor 17 is a single chain 32 which has a hook 33 on one end adapted to engage the ring 19 at the right hand or lead end of said conveyor 17. The chain 32 is shown in Figure 1 extending diagonally upwardly and outwardly along the bottom 23 of the outrigger 22 and thus over the rollers 28 and 29 on said outrigger. The chain then leads downwardly and inwardly beneath the guide member or roller 31 in the open-

ing 16 and is suitably detachably connected to an end of a flexible cable 34. The cable 34 extends above and throughout the length of the gutter 13, and thence about a roller 35 which is mounted on the barn side wall 9. The cable 34 then extends upwardly about a roller 36 on an upper portion of the barn side wall 9 and from this roller the cable 34 leads to a winding drum 37. The drum 37 is suitably mounted on a platform 38 which is suspended by uprights 39 from the barn ceiling 12. The shaft 40 of the drum 37 is rotatably mounted in uprights 41 which extend between the platform 38 and the ceiling. A second pair of uprights 42 carry a shaft 43 having pulleys 44 and 45 thereon. The pulley 44 is connected by a belt 46 to a pulley 47 on the winding drum 37. The pulley 45 on the shaft 43 is connected by a belt 48 to a motor 49 which is also mounted on the platform 38. Thus the power mechanism is located in a place where it will take up no floor space in the barn.

When the apparatus is in the position of Figure 1, the motor 49 is energized by any suitable means not shown to cause the drum 37 to wind the cable 34 thereon. This will pull the lower horizontal portion of the cable to the left and pull the single chain 32 from the outrigger 22 and into the barn above the gutter 13. This, of course, will pull the flexible conveyor member 17 to the right or out of the end of the gutter 13 and carry along with it any droppings or other material in the gutter. The shoes 30 which extend through the gutter outlet 15 will keep the conveyor 17 down against the bottom of the gutter. Otherwise there will be a tendency for the pull of the chain 32 to lift the outwardly moving end of the conveyor 17. The guide members 31 and 35 in the form of a pair of rollers and the tension on the cable 34 and chain 32 will keep these two members suspended above the gutter. The cable 34 and possibly a portion of the chain 32 are wound upon the drum 37 until the conveyor 17 has moved upwardly and outwardly on the outrigger and thence upwardly over the outrigger rollers 28 and 29 and downwardly to the bar beneath the guide member or roller 31 until the full length of the conveyor has been returned to the barn. At this point practically all of the conveyor has dropped into the barn gutter. By reason of the fact that either of the two ends of the conveyor 17 can be connected to the chain 32 said chain and the cable 34 can be pulled outwardly unwinding the cable from the reel 37. The chain 32 is then placed around the outrigger rollers and its free end is connected to that end of the conveyor 17 which lies adjacent the barn gutter outlet opening 15. The conveyor 17 is in a reverse position longitudinally and vertically from its original position, but in view of the identical structure of the ends of the conveyor and on its top and bottom sides, as shown, in Figure 5, it will function in the same manner as before.

This arrangement makes it extremely easy to return the conveyor to the gutter without having a pull cable attached to both ends of the conveyor and also without requiring a reversible power mechanism. When the chain 32 and cable 34 are pulled back for resetting the power motor 49 is merely electrically disconnected so that the motor and reel 37 will run comparatively free. To manually return the conveyor 17 to its proper position in the gutter requires considerably more work than when it is returned in the manner described above. Manual return of the chain 32 and cable 34 requires much less exertion. An-

other advantage of our invention is that the conveyor proper, namely the member 17, becomes thickly coated with cattle droppings and is a disagreeable and unclean structure to handle, whereas the chain 32 and cable 34 remain comparatively clean.

The discharge gate 25 at the upper and outer end of the outrigger 22 can be provided if desired to dump the cattle droppings either from the extreme end of the outrigger or through the opening provided by the gate 25. In the latter case it is found more convenient when loading a vehicle such as a manure spreader since the gate will direct the droppings into the spreader without dropping it to the ground or on the upper side edges of the spreader box.

It will, of course, be understood that various changes may be made in the form, details, arrangement and proportions of the various parts without departing from the scope of our invention.

What we claim is:

1. In a barn cleaner for use in a barn having a gutter and vertically aligned guide openings within one of the barn walls, one of the openings being in alignment with the gutter and comprising a discharge for the gutter, an elongated flexible conveyor adapted to lie in and move along the barn gutter, said conveyor having free ends with each end having readily releasable attaching means thereon, a separate, elongated and flexible pulling means readily attachable to and detachable from each end of said conveyor, the conveyor during the barn cleaning operation being pulled through the discharge opening of the barn to discharge the contents of gutter and back through the other guide opening with the conveyor substantially horizontally disposed with respect to the gutter and in close proximity thereto until the free end of the conveyor is pulled through the guide opening whereupon the conveyor has been reversed end for end, and the attaching means is detached from the one end of the conveyor and attached to the opposite end so that the conveyor is ready for use in the gutter.

2. In a barn cleaner for use in a barn having a gutter and vertically aligned guide openings within each of the barn walls, one of the openings being in alignment with the gutter and comprising a discharge for the gutter, an elongated flexible conveyor adapted to lie in and move along the barn gutter, said conveyor having free ends, a separate elongated and flexible pulling means readily attachable to and detachable from each end of said conveyor, and an outrigger having a conveyor receiving end adapted for positioning adjacent the discharge opening of the barn and having a guideway thereon directing said pulling means and said conveyor from the discharge opening of the barn to the other guide opening when said outrigger is so positioned, the conveyor during the barn cleaning operation being pulled through the discharge opening of the barn to discharge the contents of the gutter and back through the other guide opening with the conveyor substantially horizontally disposed with respect to the gutter and in close proximity thereto until the free end of the conveyor is pulled through the guide opening whereupon the conveyor has been reversed end for end, and the attaching means is detached from the one end of the conveyor and attached to the opposite end so that the conveyor is ready for use in the gutter.

3. A barn cleaner for use in a barn of the type having a substantially horizontal gutter and an open area in a wall of the barn positioned so that at least a part thereof furnishes a discharge for the gutter and so that a portion thereof extending above the gutter discharge portion will accommodate a flexible conveyor, said cleaner comprising an elongated, flexible conveyor constructed to convey at opposite surfaces thereof and adapted to lie in and move horizontally along the barn gutter and having free ends, a separate flexible cable having a free end readily attachable to and detachable from each end of said conveyor, and a horizontally positioned guiding element disposed transversely in relation to the gutter and about which said pulling element may be trained to guide the pulling means and the conveyor during barn cleaning operation inwardly to a position substantially overlying the gutter whereby during barn cleaning operation the conveyor may be pulled by said pulling element along the bottom of the gutter, then through the discharge opening of the barn to discharge the contents of the gutter, then over said guiding element and inwardly of the barn to be disposed horizontally above the original position of the conveyor in the gutter whereupon the conveyor has been reversed end for end and the free end of said pulling means may be detached from the one end of the conveyor and attached to the opposite end so that the conveyor will be again ready for use in the gutter.

4. A barn cleaner for use in a barn of the type having a substantially horizontal gutter and an open area in a wall of the barn positioned so that at least a part thereof furnishes a discharge for the gutter and so that a portion thereof extending above the gutter discharge portion will

5 accommodate a flexible conveyor, said barn cleaner comprising an elongated flexible conveyor constructed to convey at opposite surfaces thereof and adapted to lie in and move horizontally along the barn gutter and having free ends, a separate flexible cable having a free end readily attachable to and detachable from each end of said conveyor, a horizontally positioned guide element disposed transversely in relation to the gutter and about which said cable and said conveyor may be trained to guide the cable and the conveyor during barn cleaning operation inwardly to a position substantially overlying the gutter, winch means connected to the other end of said cable whereby during the barn cleaning operation the conveyor may be pulled by said winch and said cable along the bottom of the gutter, then through the discharge opening of the barn to discharge the contents of the gutter, then over said guiding element and inwardly of the barn to be disposed horizontally above the original position of the conveyor in the gutter whereupon the conveyor has been reversed end for end and the cable may be detached from the one end of the conveyor and attached to the opposite end so that the conveyor will be again ready for use in the gutter.
